UNITED STATES PATENT OFFICE.

JOHN RAYMOND HARRIS, OF PITTSBURGH, PENNSYLVANIA.

DESIGN FOR A SMOKER'S OUTDOOR LIGHTING DEVICE.

53,242.

Specification for Design.

Patented Apr. 29, 1919.

Application filed November 8, 1918. Serial No. 261,719. Term of patent 3½ years.

To all whom it may concern:

Be it known that I, JOHN RAYMOND HARRIS, a citizen of the United States, and a resident of Oakland Station, Pittsburgh, in the county of Allegheny and State of Pennsylvania, United States of America, have invented a new, original, and ornamental Design for a Smoker's Outdoor Lighting Device.

Reference is to be had to the accompanying drawing in which

Figure 1 is a perspective view of a lighting device embodying my new design;

Fig. 2 is a rear end view thereof.

I claim:

The ornamental design for a smoker's outdoor lighting device, as shown.

JOHN RAYMOND HARRIS.
